CLAIM

The ornamental design of the monocular viewer, as shown and described.

DESCRIPTION

FIG. 1 is a front right perspective view of a molecular viewer showing the new design;

FIG. 2 is a right view of the monocular viewer;

FIG. 3 is a top view of the monocular viewer;

FIG. 4 is a bottom view of the monocular viewer;

FIG. 5 is a left side view of the monocular viewer;

FIG. 6 is a front view of the monocular viewer; and,

FIG. 7 is a rear view of the monocular.

The broken lines showing knurling, ribs, and connection ports are for illustration purposes only and form no part of the claimed design.
